UNITED STATES PATENT OFFICE.

PETER PLANTINGA AND MARGARET PLANTINGA, OF READSBORO, VERMONT.

DESIGN FOR A GARDEN HOE.

60,259.

Specification for Design.

Patented Jan. 17, 1922.

Application filed July 22, 1920. Serial No. 398,325. Term of patent 14 years.

To all whom it may concern:

Be it known that we, PETER PLANTINGA and MARGARET PLANTINGA, citizens of the United States, both residing at Readsboro, in the county of Bennington and State of Vermont, have invented a new, original, and ornamental Design for a Garden Hoe, of which the following is a specification, reference being had to the accompanying drawing, forming part thereof, in which—

Fig. 1 is a side view of a garden hoe showing our new design;

Fig. 2 is an end view of a garden hoe showing our new design.

We claim:

The ornamental design for a garden hoe as shown.

In testimony whereof we have hereunto affixed our signatures.

PETER PLANTINGA.
MARGARET PLANTINGA.
